(No Model.)

H. W. McVICAR.

SCHOOL FURNITURE.

No. 308,921.

Patented Dec. 9, 1884.

UNITED STATES PATENT OFFICE.

HENRY W. McVICAR, OF WINCHESTER, VIRGINIA.

SCHOOL-FURNITURE.

SPECIFICATION forming part of Letters Patent No. 308,921, dated December 9, 1884.

Application filed January 18, 1884. (No model.)

To all whom it may concern:

Be it known that I, HENRY W. McVICAR, a citizen of the United States, residing at Winchester, in the county of Frederick and State 5 of Virginia, have invented certain new and useful Improvements in School-Furniture, of which the following is a full, clear, and exact description.

This invention is designed specially for 10 "school-furniture," so called, and its object is to provide capabilities of adjustments in such furniture, whereby work or exercise and study may be facilitated by the adaptation of the furniture to the size, position, and purposes 15 or needs of the user.

The invention is applicable in part to other than school-furniture, such as desks generally and draftsmen's tables.

The invention consists in the combination 20 and arrangement of parts, as hereinafter particularly set forth and claimed.

In the accompanying drawings, illustrating my invention, in the several figures of which like parts are similarly designated, Figure 1 25 is a side elevation of a combined desk and seat embodying my invention. Fig. 2 is a central vertical section of the same from front to rear. Fig. 3 is a face view on a larger scale of a friction-pad used in the joints of the 30 legs to aid in holding them in adjusted position. Fig. 4 is a section on the scale of Fig. 3, taken in the planes of line $x-x$, Fig. 1; and Fig. 5 is a partly-sectional view in the plane of line $y-y$, Fig. 1.

35 In constructing my desk I employ pairs of crossed legs $a b$, said legs being secured at their intersections by superficially roughened, rayed, or otherwise friction-surfaced plates c , interposed between the two legs of each pair 40 at those points, and screws e , thumb-nuts f , and washers g , which plates, screws, nuts, and washers constitute friction-clamps, and of which there are many well-known and common forms and equivalents. The legs a in use 45 will be pivotally fastened at their lower ends, as by angle-plates h , secured to the floor, and on which the legs may move as upon a pivot. The legs b will be held by the friction-clamps in any position that may be given. The pairs 50 of legs are united by a book-receptacle, i , fixed to the legs a .

To the upper ends of legs $a b$ are jointed

arms $j k$, respectively, and these arms at their other ends engage longitudinally-slotted bars l , depending transversely from the under side 55 of the top m of the desk. The engagement of the arms $j k$ with these slotted bars is rendered adjustable by means of screws n , fast in said arms, extending through the slots in said bars, and engaged by thumb-nuts o , suitable friction-washers, $p q$, being interposed between the 60 nuts and bars and bars and arms, respectively, to make a secure fastening. These bars may be notched or roughened, as at l' , to insure the fastening.

The seat is composed of a back, r , having lugs s near its head, pivoted to the upper ends of legs $a a$, and at its bottom provided with arms t , slotted and notched substantially as shown, and engaged by set-screws u with the 70 legs b , and to this back is separately pivoted or hinged the folding seat v , of approved construction. By loosening the jointing-clamps of the crossed legs the ends of the said legs may be moved toward or from each other, to 75 thereby increase or diminish the height of the desk, and in this movement the seat will participate. Now, as the seat attached to one desk is occupied by the user of the desk in front, and as it may be undesirable to raise or 80 lower such seat beyond a given height, I have provided for a separate adjustment of the desk-top to accommodate the user of the desk, so that if the seat is to be high the full adjustment of the seat may be had and the desk-top lowered by the arms $j k$, as indicated by 85 the broken lines, Fig. 2. So, also, if the seat is to be below, the desk-top is raised by the arms $j k$, as in full lines, Fig. 1, and the elevation of the desk-top may be varied by the scholar to 90 any extent between its two limits just noted; but the movement of the legs of the desk should be under the control of the teacher or other authority. Furthermore, by lowering the arms k various inclinations of the top may be secured for drafting or other purposes, as indicated in broken lines, Fig. 1.

By changing the point of engagement of the notched arms t with the screws u , the seat may be swung on its pivotal connections with the 95 legs a toward or from the legs, and so decrease or increase its height and vary its inclination.

I have shown screws as the means for jointing some of the parts; but, as is obvious, the

most suitable known jointing devices will be employed.

What I claim is—

1. The combination, with the connected seat, desk-top provided with slots, and pairs of crossed legs jointed and clamped together at the crossing to admit of the movement of the legs to obtain a vertical adjustment of the seat, desk-top, and legs, of the arms *j k*, interposed between the legs and desk-top and forming the joints between them, and admitting of the independent adjustment of the desk-top as to its height and angle, and the adjustable arms *t*, connecting the pivoted seat with the legs to provide for the separate adjustment of the inclination of the seat, substantially as shown and described.

2. The combination, substantially as shown and described, of the pairs of crossed legs *a b*, secured at their intersection by clamps, the desk-top provided with side slots and arms jointed to and connecting said top and legs, and fastening devices for retaining said arms at desired positions within the slots, the seat pivoted by its back to the legs *a* and connected

with the legs *b* by adjustable arms, as and for the purpose described.

3. A desk-top having side slots and its pairs of crossed legs provided with clamping devices at their intersections to hold them in adjusted position, combined with arms *j k*, jointed to and connecting such top and legs, and clamping devices to secure the said arms in adjusted position to the desk-top to vary the height and angle of the top, substantially as shown and described.

4. The combination, with the desk and adjustable legs, of the seat pivoted to the said legs at their upper ends, and arms *t*, and fastening devices connecting the seat at its lower end through said arms with the desk-legs, to permit the change of inclination of the seat independently of the adjustments of the desk, substantially as shown and described.

In testimony whereof I have hereunto set my hand this 17th day of January, A. D. 1884.

H. W. McVICAR.
